FOLDING BOOKREST

John Haig H. Tiryakian, Mount Vernon, N. Y.

Application October 3, 1942, Serial No. 460,639

10 Claims. (Cl. 45—80)

This invention relates to article supports or holders and more particularly to devices for supporting books or sheets in convenient position for reading, though it is noted that in some of the claims the invention is not limited to the specific purpose of the support or holder.

One object of the invention is to provide an improved device or apparatus of this kind which may be collapsed to occupy a very small space, and which provides a strong, rigid and very convenient holder when erected.

Other objects of the invention are to provide in a device of this kind, improved locking means for locking the device in erected position, and improved means for holding the leaves or sheets in place when in use.

Additional objects of the invention are to effect simplicity and efficiency in such apparatus and to provide an extremely simple device or apparatus of this kind which is economical, durable, and reliable in operation, and economical to manufacture.

Still other objects of the invention will appear as the description proceeds; and while herein details of the invention are described in the specification and some of the claims, the invention as described in the broader claims is not limited to these, and many and various changes may be made without departing from the scope of the invention as claimed in the broader claims.

The inventive features for the accomplishment of these and other objects are shown herein in connection with several book or sheet supports or holders, each of which briefly stated, includes a base of suitable board on which a book or leaf rest is hinged at its lower margin for movement from the base to a raised position in which it is held by a suitable strut. A ledge is secured across the front of the base near the front margin of the rest.

In two of the illustrated forms the ledge has its rear edge hinged to the outer front margin of the rest and is adapted to lie substantially in the plane of the rest when the rest is in lying position; and automatic means are provided for raising the ledge whenever the rest is raised.

In two forms of the invention additional leaf holding devices are provided, and these may be provided in all the forms if desired.

In the three illustrated forms of my invention the base, rest and strut are made of thin fiber-board, card-board, wood, plastic or other suitable material, which may be painted or enameled with suitable colors or not as desired.

In all forms suitable means are provided for 55

locking the struts in raised position, but these means may be omitted if desired.

In the accompanying drawings showing, by way of example, several of many possible embodiments of the invention,

Fig. 1 is a side elevation of the form of the invention of Figs. 1 to 4;

Fig. 2 is a front elevation;

Fig. 3 is a fragmental plan showing the strut locking means looking from the line 3—3 of Fig. 1;

Fig. 4 is an enlarged sectional view taken on the line 4—4 of Fig. 2;

Fig. 5a is a side elevation of a book rest having parts similar to Figs. 1 and 5;

Fig. 5 is a side elevation showing the form of invention of Figs. 5 to 7 erected;

Fig. 6 is a fragmental rear elevation of the device of Fig. 5;

Fig. 7 is a side edge elevation of the device of Fig. 5 collapsed and folded flat;

Fig. 8 is a side elevation showing the device of Figs. 8 to 11 erected;

Fig. 9 is a fragmental plan showing the strut locking means;

Fig. 10 shows a section taken on the line 10—10 of Fig. 9;

Fig. 11 is a fragmental plan looking from the line 11—11 of Fig. 8; and

Fig. 12 is a rear view of the rest of Fig. 5, showing a book or sheet holder.

In all illustrated forms of the invention, the book holder comprises a substantially rectangular base 10 of suitable board, to which the leaf rest 11 is hinged as will be explained. The leaf rest is of thin board and is provided along the lower margin of its lower face with a thickening strip 12 of board adhered to said margin flush with the free edge thereof for thickening said margin. A flexible strip 14, or strips 14, 15, of fabric, leather or the like are adhered to and along the lower margin of the lower and upper faces of said strip 12 and to a zone of said support 10 parallel and near to the front edge thereof to form a hinge between the lower edge of the strip and said base whereby the rest is hinged to the base for movement to positions near and parallel with the base and at an angle thereto.

Flexible strips of material 17 adhered to an edge of a rectangular strut board 18 (Figs. 1 and 8) or 18' (Fig. 5), and across the lower face of the rest 11 along a zone near and parallel to the upper edge of the rest forms means for hinging the rest and board together for relative move-

ment.

ment to a position flat against each other or at an angle to each other, the distance between the upper and lower edges of the strut board 18 or 18' being less than the distance between the hinge lines of said flexible strips 14 and 17, whereby said board may lie flat against the top face of the base, with the bottom face of the rest lying flat on the board thus to form a compact assembly for shipping or storage.

The strut boards are held in raised position, as in Figs. 1, 5 and 8 by different means.

In Fig. 1, a pair of spaced parallel cleats 20, 21 are secured on the rear margin of the base. These cleats are the same thickness as said strip 12, and said rest 11 may lie on said strip and cleats. The strut board 18 being as thin as said strip and cleats and shorter than the distance between the cleat 21 and the thickening strip 12 is disposable between said cleat 21 and strip 12.

The mid part of said cleats 20, 21 and the lower edge of the strut therebetween are provided with transverse aligned apertures 23, 24, 25, receiving a bolt 26 slidable in said apertures to lock the strut in place as shown in Fig. 1. This holds the strut in place when the whole device is lifted by grasping the rest 11.

If desired, the strip 21, said bolt 26 and said apertures may be omitted, since the strut raised as in Fig. 1 tends to move rearwardly and will be stopped by the one cleat.

In the form of invention of Fig. 5 the rest 11 and strut board 18' are tall for long sheets or books; and the strut board 18' when lying on the base extends rearward of the cleats, as in Fig. 7, and has two rectangular cut-outs 28 adapted to receive aligned cleats 20' to allow the strut board to lie flat upon the base. The rear part of the base 10 of Fig. 7 just forward of the line of the forward edges of the cleats 20' is provided with a large cut-out 29 having one straight edge extending perpendicularly forwardly from the midpart of said edge line, the cut-out being extended laterally from said straight edge. A latch piece 30 of base material cut from, and of the same shape as, said large cut 29 and adapted to lie in and fill the cut-out has a straight margin 31 hingedly connected by strips 32 of flexible material to said straight edge, so that the piece is adapted to move from the cut-out to a plane perpendicular to said base and the strut board when erected, the upper part of the rear edge of said piece 30 being provided with a slightly projected rear lug or projection 34 adapted when the piece and strut board are upright to engage in a slot 35 in the lower part of the strut board to hold the piece against the strut and to hold the strut in place against the cleats and base.

In the forms of the invention of Figs. 1 to 7 a narrow ledge or strip 38 of board as thick as said rest 11 has its upper rear edge 39 (Fig. 4) hingedly secured by a flexible strip 40 to the outer front edge of the rest. A lifting bar 41, 42 along the front edge of the base and composed of two superposed strips of board 41 and 42, together as thick as the rest 11 and said thickening strip 12 together, has its lower front edge hingedly secured by means of flexible strips 43, 43' to the upper front edge of the base 10.

The lower front edge of the ledge is hingedly secured to the rear meeting edges of the superposed strips by means of a strip 45 adhered to the bottom of the ledge 38 and between the strips 41, 42.

The width of said bar 41, 42 and ledge 38 is

about equal to the distance between the upper front edges of the base and rest when the rest is in lying position, whereby the bar, ledge, rest and strut board 18 may simultaneously lie in compact relation with the top face of the bar and ledge in the same plane, as in Fig. 4, and whereby when the rest is moved to its raised position, as in Fig. 1, the distance between the upper front edges of the rest and base becomes less than the combined width of the bar and ledge, causing the bar 41, 42 and ledge 38 to buckle upwardly on their hinge connection to dispose the ledge at an angle to the raised rest to form a support for the bottom edges of a book or sheets resting against the rest.

In the form of invention of Figs. 1 to 4, a gib 48 secured along the top face of said lifting bar and having undercut sides, carries a pair of slide plates 49 resting on said gib and having in-turned lower flanges 50 frictionally engaged under the undercut sides of the gib to allow longitudinal sliding movement of the plates longitudinal to the gib. Flat spring clips 53, 54 are pivoted as at 55 at their inner ends on said plates 49 respectively, each clip having an upwardly curved and rounded outer end 56 (Fig. 1). Each clip is adapted to be pivotally moved to be disposed longitudinally of the gib, as in the dotted line of Fig. 2, and may overlap each other. The clips may be moved lateral to the gib over the rest 11, as in the solid lines of Fig. 2, to engage and hold sheets or the leaves of a book, each spring being inherently curved to press upon and hold the leaves in proper position for reading. A keeper plate 58 is disposable over the springs when overlapped and provided with in-turned lower flanges 59 engaging under the undercut edges to permit the keeper plate to slide on the gib to release the springs. Said springs are also releasable by sliding the slide plates 49 away from the keeper plate 58.

In the form of invention as in Figs. 8 to 11, the leaf-rest 11 is hinged at the lower front edge of the rest by the strips 14 to a line of said base a short distance to the rear of the front edge of the base. The support or ledge 38' for engaging the bottom edge of the book or sheets comprises a thick bar composed of one or several thicknesses of material secured fast on the base 10. The ledge strip 38' has its rear face 39' disposed at an angle to the rest 11 when the rest is raised.

A pair of aligned cleats 20a, fast on the rear margin of the base, have their ends 60 spaced apart to form a recess 61 in which is fixedly mounted the outer end 62 of a spring clip 62, 63 extending frontwardly of said recess and having its free end 63 and intermediate part spaced from the base and adapted when the lower margin of the strut is slid on the base to the cleats, to be received by a transverse aperture 64 in the lower edge of the strut.

It is understood that the various illustrated ledges 38, 38', the strut locks and the clips 53, 54 may be used with any of the illustrated forms or other suitable forms of the invention, and that the forms of the invention as herein claimed are not limited in the broader claims to the various details for carrying out the invention.

The sheet or book holder of Figs. 5, 5a, 6 and 12 may be applied to any of the species, and comprises a strip 70 of wood or other material secured across and flat against the rear face of the rest 11 and is provided in its unexposed face with parallel longitudinal grooves 71 (Fig. 5a) cooperating with the rest 11 to form bores in which

are slidably received rods or wires 72, each provided with a hooked end 73, the hooked ends being disposed near opposite side edges of the rest respectively and disposable flat against said rear face. The hook is adapted, when the wires are outwardly drawn in the grooves to be placed frontward of the rest for holding sheets on the rest or to hold a book open on the rest. If desired, instead of the grooves 71, the strip 70 may be provided with longitudinal bores 71' (Fig. 5) receiving the wires 72.

The invention claimed is:

1. A manuscript or book holder comprising a base; a board leaf-rest provided along the lower margin of its lower face with a thickening strip; a means forming a hinge between the lower front edge of the strip and a line of said base parallel, and near to, the front edge thereof; means for holding the rest raised; a narrow ledge having its upper rear edge hinged to the outer front edge of the rest; superposed strips forming a lifting bar as thick as the rest and said thickening strip together and having its lower front edge hinged to the upper front edge of the base; the lower front edge of the ledge being hingedly secured to the rear meeting edges of the superposed strips; the width of said bar and ledge being about equal to the distance between the upper front edges of the base and rest when the rest is in lying position; whereby the bar, ledge and rest may simultaneously lie in compact relation, and whereby when the rest is moved to its raised position, the distance between the upper front edges of the rest and base becomes less than the combined width of the bar and ledge, causing the bar and ledge to buckle upwardly on their hinge connection to dispose the ledge at an angle to the raised rest.

2. A holder comprising a substantially rectangular base of suitable material; a leaf rest of thin board provided along the lower margin of its lower face with a thickening strip of board adhered to said margin flush with the free edge thereof for thickening said margin; a flexible strip adhered to and along the lower margin of the lower face of said strip and to a zone of said support parallel, and near to, the front edge thereof to form a hinge between the lower edge of the strip and said base whereby the rest is hingedly connected to the base for movement to positions near and parallel with the base and at an angle thereto; means to hold the rest raised; a narrow ledge strip of board as thick as said rest having its upper rear edge hingedly secured to the outer front edge of the rest; a lifting bar along the front edge of the base composed of two superposed strips of board, together as thick as the rest and said thickening strip together; the lower front edge of the bar being hingedly secured to the upper front edge of the base.

3. A support comprising a base; a leaf-rest hinged at its lower margin to a line of said base near the front thereof; a pair of spaced parallel cleats on the rear margin of the base; a strut board hinged across the lower face of the rest near the upper edge thereof; the strut board being engageable between said cleats; the mid part of said cleats and the lower edge of the strut therebetween being provided with transverse aligned apertures; and a bolt slideable in said apertures to lock the strut in place and having a downturned outer end.

4. A holder comprising a support; a rest on the support; a strip of wood secured across and flat against the rear face of the rest and provided

in its unexposed face with parallel longitudinal grooves cooperating with the rest to form bores; rods or wires slidably received in said grooves respectively and each provided with a hooked end, the hooked ends being disposed near opposite side edges of the rest and disposable flat against said rear face, and adapted when the wires are outwardly drawn in the grooves to be placed frontward of the rest for holding sheets thereon or a book open thereon.

5. A folding support comprising a base; a leaf-rest provided at the lower margin of its lower face with a thickening strip secured thereto; means hinging the lower front edge of the strip to a line of said base near the front thereof, whereby elevating the rest causes the upper front edge thereof to move forward; a cleat on the rear of the base the same thickness as said strip and on which said rest may lie; a strut board hinged across the lower face of the rest near the upper edge thereof; the strut board being as thin as said strip and cleats and shorter than the distance between its hinged part and the thickening strip; a ledge strip having its upper rear edge hinged to the outer front edge of the rest; a lifting bar having its lower front edge hinged to the base; the lower front edge of the ledge being hinged to the rear of the bar at a line spaced above the bottom of the bar; the width of said bar and ledge being substantially equal to the distance between the upper front edge of the rest and the lower front edge of the bar when the rest is in lying position; whereby raising the leaf rest causes the ledge strip to buckle upwardly, and means to hold the strut board against the base, whereby the last mentioned means holds the strut board, rest and ledge in elevated position.

6. A support comprising a base; a leaf-rest provided at the lower margin of its lower face with a thickening strip secured thereto; means hinging the lower front edge of the strip to a line of said base near the front thereof; a cleat on the rear of the base the same thickness as said strip and on which said rest may lie; a strut board hinged across the lower face of the rest near the upper edge thereof; the strut board being as thin as the thickening strip and cleats and shorter than the distance between its hinged part and the thickening strip; means to hold the strut board against the cleat and the base; a ledge strip having its upper rear edge hinged to the outer front edge of the rest; a lifting bar having its lower front edge hinged to the base; the lower front edge of the ledge being hinged to the rear of the bar at a line spaced above the bottom of the bar; the width of said bar and ledge being substantially equal to the distance between the upper front edge of the rest and the lower front edge of the bar when the rest is in lying position, so that upon raising the leaf-rest, the front marginal portion of the upper face thereof forces the ledge strip forwardly causing the latter lifting bar to buckle upwardly.

7. A folding support comprising a base; a leaf-rest provided with a thick front marginal portion; means hinging the lower front edge of said marginal portion to a line of said base near the front thereof, whereby elevating the rest causes the upper front edge of the rest to move forwardly and downwardly; means for holding the leaf-rest in raised position; a ledge strip having its upper rear edge hinged to the upper front edge of the rest at least as far forward as said line; and

a lifting bar having its lower front edge hinged to the base; the lower front edge of the ledge being hinged to the rear of the bar at a line spaced near and above the bottom of the bar.

8. A folding support comprising a base; a leaf-rest provided at the lower margin of its lower face with a thickening strip secured thereto; means hinging the lower front edge of the strip to a line of said base near the front thereof, whereby elevating the rest causes the upper front edge thereof to move forward; means for holding the leaf-rest in raised position; a ledge strip having its upper rear edge hinged to the outer front edge of the rest at least as far forward as said line; and a lifting bar having its lower front edge hinged to the base; the lower front edge of the ledge being hinged to the rear of the bar at a line spaced near the bottom of the bar; the width of said bar and ledge being substantially equal to the distance between the upper front edge of the rest and the lower front edge of the bar when the rest is in lying position; whereby raising the leaf rest causes the ledge strip to be buckled upwardly.

9. A folding support comprising a base; a rest over the base having a front margin having its lower front edge hinged to the base on a line at the front part of said base; a ledge having its upper rear longitudinal edge hinged to the rest on a line at the upper front edge of the rest; and a lifting bar having its front edge hinged to the base on a line over the base and its rear edge hinged to the ledge on a line at the front edge of the ledge; said line at the upper front edge of the rest being at least substantially as far forward as said first named line of the base, and said line at the front edge of the ledge being disposed above a plane passing through said line at the upper front edge of the rest and said line at the front edge of the lifting bar when the rest is in lying position, and said

front margin being thick, whereby raising the rest causes the rear edge of the ledge to move considerably forwardly and downwardly and causes the ledge automatically to buckle upwardly.

10. A holder comprising a base; a leaf-rest thickened at the front margin of its lower face; means hinging the lower front edge of the thickened margin to a line of said base near the front thereof; a strut means for holding the rest raised; a ledge strip having its rear edge hinged to the outer front edge of the rest; a lifting bar having its lower front edge hinged to the base; the lower front edge of the ledge being hinged to the rear of the bar at a line spaced above the bottom of the bar; the width of said bar and ledge being substantially equal to the distance between the upper front edge of the rest and the lower front edge of the base when the rest is in lying position; a gib secured along the top face of said lifting bar and having undercut sides; a pair of slide plates resting on said gib and having inturned lower flanges frictionally engaged under the undercut edges to allow longitudinal sliding of the plates; flat spring clips pivoted at their inner ends on said plates respectively, and each having an upwardly curved and rounded outer end; each clip being adapted to pivotally move to be disposed longitudinally of the gib in overlapping position, or lateral thereto to engage leaves of a book, each spring being inherently curved to press upon and hold open the leaves; and a keeper plate disposable over the overlapped springs and provided with inturned lower flanges engaging under the undercut edges to permit the keeper plate to slide on the gib to release the springs; said springs being releasable also by sliding the slide plates away from the keeper plate.

JOHN HAIG H. TIRYAKIAN.
